UNITED STATES PATENT OFFICE.

FREEBORN F. RAYMOND, 2d, OF NEWTON, MASSACHUSETTS.

HEEL-NAILING MACHINE.

SPECIFICATION forming part of Letters Patent No. 280,399, dated July 3, 1883.

Application filed February 13, 1883. (No model.)

To all whom it may concern:

Be it known that I, FREEBORN F. RAYMOND, 2d, of Newton, in the county of Middlesex and State of Massachusetts, a citizen of the United States, have invented a certain new and useful Improvement in Heel-Nailing Machines, of which the following is a full, clear, and exact description, reference being had to the accompanying drawings, forming a part of this specification in explaining its nature, in which—

Figure 1 is a rear elevation of a heel-nailing machine containing my invention. Fig. 2 is a plan view thereof. Fig. 3 is a side elevation, and Fig. 4 is a detail view, hereinafter referred to.

This invention is an improvement upon that described in Letters Patent No. 252,215, dated January 10, 1882, and No. 259,687, dated June 20, 1882, granted Henry A. Henderson, assignor; and it consists in a heel-nailing machine having the templet and nail-holder, or either, provided with automatic movements, as and for the purposes hereinafter specified. In said patented machine the templet and nail-holder are moved at proper intervals by the attendant or boy who assists in operating the machine. The templet must be moved into position beneath the awls, when the heel-blank is to be punctured, immediately after the work has been placed in position, and before the awls are reciprocated, and after the heel has been punctured and the awls withdrawn the nail-carrier must be pushed forward upon the templet-plate to a position over the templet, when the drivers are caused to reciprocate to drive the nails fed by the nail holder and carrier through the templet into the heel-blank; or, if drivers alone are used, the nail holder and carrier must be pushed forward by hand immediately before the drivers are reciprocated, and before the machine can be again operated it is necessary that the templet and nail holder and carrier be drawn back to their original position. If, after the nails are driven, the heel-spanker is caused to be reciprocated, it is necessary, of course, to remove the templet and nail-holder, or the nail-holder before it can be brought into operation; and if by accident the nail-holder and templet shall not be withdrawn when specified and the awls or spanker brought into position and recipro-

cated some damage would be done the machine. I have therefore conceived it desirable to provide the nail-holder and templet with automatic movements, whereby they may be fed forward and withdrawn at stated intervals without requiring the care or attention of the operator or his assistant. This construction is an advantage in another respect, in that it gives the assistant more time to help the operator. In order that the operator may have full control of the movement of these parts, I prefer to so arrange the operative mechanism, when awls and a spanker are used in addition to drivers, that the movement of one to take the place of the other shall also bring into position the mechanism for operating the templet or nail-holder, as the case may be.

Referring to the drawings, A represents the cross-head of the machine. It is reciprocated by mechanism like or substantially like that described in said Letters Patent, or in any other desirable way, and it supports or carries the revolving head a, which may have an arm, a', for supporting the awls a², an arm, a³, for supporting the drivers a⁴, an arm, a⁵, supporting the spanker a⁶.

Upon the shaft a⁷, supporting the revolving head at its rear end, I have attached the gear-wheel a⁸, which operates the gear-wheel a⁹, also secured to the cross-head directly, or by means of an intermediate gear. This gear-wheel a⁹ carries upon its face the projections a¹⁰, which extend outwardly therefrom, and are adapted by the movement of the gear-wheel a⁹ to be brought into position successively over the slide-bars B B'. Each of these slide-bars is supported by the bracket b, bolted to the left-side frame of the machine, or otherwise suitably supported, and each is held up or supported and returned to normal position by the coiled spring b'. The lower ends, b², of these bars B B' are inclined or wedge-shaped, as represented, and the downward movement thereof actuates or moves horizontally the connecting-bars b³ b⁴, with the ends of which they contact. The connecting-bar b³ is pivoted at its outer end to the lever b⁵, which is pivoted at b⁶ to a bracket b⁷, and the other end, b⁸, of this lever bears against the end of the templet-plate. The horizontal bar b⁴ is connected with and operates the lever b¹⁰, which is also pivoted to

the standard b^7 , and bears upon or is attached to the rear end of the nail-holder plate B^3 . It is readily seen that upon the downward movement of the cross-head the inclines upon the 5 slide-bars $B B'$ move the connecting rods or bars $b^3 b^4$, and cause them to move the levers $b^5 b^{10}$, and therefore move the templet and nail-holder plates.

As the machine is generally operated it is 10 necessary that the templet-plate shall be moved into position first, and when the machine is thus operated one of the projections a^{10} upon the gear or disk a^9 must be brought into position over the slide-bar B upon the moving of 15 the awls into position. Upon the downward movement of the cross-head the templet is moved into position, and the movement of the templet must be sufficiently rapid to bring it into position before the awls, in their downward movement, shall reach it. The templet having been moved into position, the awl-block moves it downward vertically, and consequently there must be a downwardly-extending portion b^{12} upon the end of the templet-plate, in order that the end of the lever 25 b^8 shall bear against some portion of the plate while it is being moved downward. As the cross-head then lifts, releasing the lever b^8 by moving its operative slide out of connection with the bar b^5 , and as a spring, C , is used 30 for returning the templet-plate to its original position, as hereinafter explained, it is necessary to lock the templet-plate after it has been automatically pushed into position by the 35 lever b^8 , and this is effected by means of the catch D , (see Fig. 4,) which is attached at d , in the recess d' , to the table d'' , and automatically shuts behind the templet by spring-pressure, and the projection d'' upon the nail-holder, 40 when the nail-holder is moved into position, throws down this catch and holds it down, releasing the templet-plate and permitting the spring C to return the templet to its normal position on the upward movement of the cross-head. The awls having been driven and withdrawn and the templet locked in position, the drivers are next moved into place. This causes 45 the disk or gear a^9 to be revolved sufficiently to bring the other of the projections a^{10} over the sliding bar B' , and the downward movement of the cross-head causes the nail-carrier to be moved automatically into proper position to discharge its nails into the templet and to receive the drivers. It is held in this 50 position during the descent of the drivers by means of the sliding bar B' , which acts as a stop or catch in holding the connecting-bar b^3 stationary at the end of its outward movement; but upon the upward movement of the cross-head, the bar b^3 being free, the lever b^{10} is released, and the nail-holder having unlocked the templet, the springs $C C'$ draw both the templet and nail-holder back to their original 55 position, and in so doing cause the connecting- 60 rods $b^3 b^4$ to be returned to their normal position. The length of the incline upon the slide-bars $B B'$ must be such that the templet and

nail-holder be moved into position before the awls or drivers shall descend far enough to prevent such a movement.

In order to vary the length of throw of the levers $b^5 b^6$, they may be provided with a slot and movable fulcrum-pin, whereby upon moving the fulcrum-pin in the slot the extent of movement of the ends of the levers will be varied, according to direction of the movement of the pin.

In case awls should not be used the nail-holder only will be used, and in that event it will be operated as the nail-holder herein described is operated.

Of course there are many mechanical equivalents for the mechanism herein described for giving the templet and nail-holder, or either of them, the automatic movements herein specified, and I do not intend to confine myself to the specific construction herein described, but propose to use as a substitute therefor any other suitable mechanism for providing these automatic movements to the templet and nail-holder, or either, from a portion of the machine which is actuated by power.

It is not necessary that the templet and nail-holder, or either of them, be located in relation to the jack and drivers, as represented, for they may be upon one side or the other of the machine, if desired.

It will be observed that the downward movement of the awl and drivers causes the templet and nail-holder to be brought into operative position, and that the reverse movements of the drivers cause the reverse movement or withdrawal of the templet and nail-holder, and that, therefore, the templet and nail-holder cannot by accident be left projecting or partly projecting from their supports when not in use.

The jack or support for the work (not shown) preferably has a horizontal movement upon the table or bed e , as described in said patent, and any suitable heel-blank and shoe-centering devices may be employed. In lieu of the revolving head, the sliding head of said Patent No. 252,215 can be used, in which case the projections a^{10} , instead of being upon a revolving disk, are upon the side of the sliding head.

In case it shall be desirable to give the sliding bars $B B'$ more throw than they now have, in order that the inclines or cam-surfaces b^2 may be longer and more gradual, a lever for each bar can be arranged between the cross-head and the end of the bar, with its fulcrum nearer to the cross-head. If this construction is employed, of course the slide-bars will be moved from the cross-head sufficiently to allow the use of levers, and of course by the use 120 the movement communicated to them by the cross-head is increased, so that the slide-bars $B B'$ and their cams or inclines may have any given extent of movement.

I may use the retracting-springs $C C'$, or either of them, without the remainder of the automatic mechanism, if I desire; and for the purposes of this invention it is of course immaterial whether a templet-plate or nail-

holder, or either of them, is actuated upon a straight line, or whether they are revolved upon a center, as described in my Letters Patent No. 271,117, or otherwise moved into operative position.

I may use for presenting the work to the heel-nailing mechanism either the jack described in the above-named patents or any other suitable one.

10 I am aware that the patent to McKay and Fairfield of July 21, 1874, No. 153,360, and that to Fisher, dated December 13, 1881, No. 250,654, describe a class of machines which may properly be called "heel-forming" or "heel-15 preparing" machines, in that they form or make the heel-blank from a number of heel-lifts by compression, and prepare the heel-blank for attachment to the sole of a boot or shoe by perforating it and filling the perforations with 20 nails partly driven into them. This class of machines is used as an auxiliary to the heel-attaching machine—that is, the machine that fastens the heel-blank to the soles of a boot or shoe; and the principal heel-attaching machine which employs such auxiliary heel forming and loading machine is that made by McKay & Bigelow Heel-Nailing Machine Association, and is known as the "McKay & Bigelow heel-nailing machine." My invention 25 does not belong to this class of machines. It does not employ a separate or auxiliary heel-forming mechanism. The unperforated heel-blank is compressed directly upon the outsole of the boot or shoe, and is nailed directly there- 30 to without any preparatory loading by another machine. This class of machine is well described in the patents above referred to. The machines made under said patents have a templet and a heel-holder which are adapted 35 to be moved by hand into and out of operative position. While this method of operation answers very well, yet it is not altogether free from objection, in that the operator or his assistant may not move either the awls, 40 drivers, or heel-spanker, or the templet or nail-holder at the proper time, and if this is not done an accident or breakage of the machine upon the next reciprocation of the cross-head may occur. In order to avoid this liability 45 to accident, as well as to increase the speed of the machine and lighten the work of the assistant, I have devised a machine which is in many respects like that described in said patent, but which has, in lieu of the hand-moved 50 templet and nail-holder, an automatically-moved templet and nail-holder.

It will be observed that the retracting-springs C C' serve two purposes: first, they act to withdraw the templet-plate and the 55 nail-holder plate to their inoperative positions upon the withdrawal of the stops which hold them in their operative position—that is, in a position to co-operate with the awls and drivers; second, they act as a safety device in withdrawing the plates to that inoperative position when they are not automatically moved into operative position, in case the operator or

his assistant should not have moved them sufficiently far to engage with the stops, or to come into operative position with the awls and 70 drivers.

Having thus fully described my invention, I claim and desire to secure by Letters Patent of the United States—

1. In an organized heel-nailing-machine, the 75 combination of a reciprocating gang of awls with a templet moved automatically into and out of operating position with the awl by means substantially as set forth, all substantially as and for the purposes described.

2. In an organized heel-nailing machine, the combination of a reciprocating gang of drivers, with a templet moved automatically into and out of operative position with the drivers by means substantially as set forth, all 85 substantially as and for the purposes described.

3. The combination of a reciprocating gang of drivers and a nail-holder moved automatically into and out of operative position with the drivers by means substantially as set forth, 90 all substantially as and for the purposes described.

4. In an organized heel-nailing machine, the combination of a reciprocating gang of drivers and a templet and nail-holder moved 95 automatically into and out of operative position with the drivers by means substantially as specified, all substantially as and for the purposes described.

5. In an organized heel-nailing machine, the 100 combination of a gang or group of awls, a gang or group of drivers brought successively into the same operative position, and means for reciprocating them, substantially as specified, with a templet and nail-holder adapted to be 105 moved automatically and successively into operative position by means substantially as set forth, all substantially as and for the purposes described.

6. The combination, in an organized heel-nailing machine, of a group or gang of drivers, and a heel-spanker adapted to be brought successively into the same operative position, substantially as specified, and means for reciprocating them with a templet moved automatically 115 into operative position before the reciprocation of the drivers, and out of the operative position before the reciprocation of the spanker by means substantially as set forth, 120 all as and for the purposes described.

7. The combination, in an organized heel-nailing machine, of a gang or group of drivers, and a heel-spanker adapted to be brought successively into the same operative position, and means for reciprocating them, with a nail-holder moved automatically into operative position before the reciprocation of the drivers, and withdrawn from the operative position after the reciprocation of the drivers and before the spanker is brought into operation, 130 by means substantially as specified, all substantially as and for the purposes described.

8. The combination, in a heel-nailing machine, of a gang or group of drivers and a

heel-spanker adapted to be brought successively into the same operative position, with a templet and a nail-holder moved automatically into operative position and withdrawn automatically after the reciprocation of the drivers and before the spanker is reciprocated, all by means substantially as specified, and for the purposes described.

9. The combination, in a heel-nailing machine, of a gang or group of awls and a gang or group of drivers adapted to be brought successively into operative position, and means, substantially as specified, for reciprocating the same, with a templet and connecting mechanism, substantially as specified, whereby the movement of the awls into operative position and their reciprocation causes the templet to be automatically moved into operative position, all substantially as and for the purposes described.

10. The combination of the templet B², the lever b⁵, operated as specified, and the spring C, all substantially as and for the purposes described.

25 11. The combination of the nail-holder plate B³, the lever b¹⁰, operated as described, and spring C', all substantially as specified, and for the purposes set forth.

12. The combination of the templet B², the lever b⁵, and mechanism for moving the lever automatically, all substantially as and for the purposes described.

13. The combination of the nail-holder B³, the lever b¹⁰, and means for automatically operating the lever, all substantially as and for the purposes specified.

14. The combination, in an organized heel-nailing machine, of a jack or support for the boot or shoe, adapted to have a horizontal movement imparted to it, with a templet, B², moved automatically into operative position, substantially as specified, and an automatic locking device for locking it in that position, all substantially as and for the purposes described.

45 15. The combination, in an organized heel-nailing machine, of a templet moved automatically into position, substantially as specified, and automatic locking device for locking it in said position, and means for unlocking it, substantially as specified, all as and for the purposes described.

16. The combination, in an organized heel-nailing machine, of a templet moved automatically into operative position, substantially as specified, and automatic locking devices for locking it in said position, with a nail-holder moved automatically into operative position, substantially as set forth, and an automatic locking device for locking it in said position, all substantially as and for the purposes described.

17. In a heel-nailing machine, the combination of a sliding templet-plate, B², with the retracting-spring C for automatically returning the templet-plate to its inoperative position, all substantially as and for the purposes described.

18. In a heel-nailing machine, the combination of the sliding nail-holder plate B³ with the retracting-spring C', adapted to automatically return the nail-holder plate to its inoperative position, all substantially as and for the purposes described.

19. The combination, in an organized heel-nailing machine, of a jack for holding and presenting the work to the nailing mechanism, a templet-plate moved automatically into and out of operative position by means substantially as specified, and a gang or group of drivers and means for reciprocating the same, all substantially as and for the purposes described.

20. The combination, in a heel-nailing machine, of the sliding templet-plate B², a stop, D, for automatically locking the same in operative position, and the retracting-spring C, whereby upon the release of the stop the templet-plate is automatically moved from an operative to an inoperative position, all substantially as and for the purposes described.

21. The combination, in a heel-nailing machine, of the sliding nail-holder plate B³, a stop for automatically locking the same in operative position, and a retracting-spring, C', whereby upon the release of the stop the nail-holder plate is automatically moved from an operative to an inoperative position, all substantially as and for the purposes described.
